UNITED STATES PATENT OFFICE.

DAVID H. EBINGER, OF COLUMBUS, OHIO, ASSIGNOR TO THE D. A. EBINGER SANITARY MFG. CO., OF COLUMBUS, OHIO, A CORPORATION OF OHIO.

DESIGN FOR A WATER COOLER.

Application filed October 15, 1926. Serial No. 19,359. Term of patent 14 years.

To all whom it may concern:

Be it known that I, DAVID H. EBINGER, a citizen of the United States, residing at Columbus, in the county of Franklin and State of Ohio, have invented a new, original, and ornamental Design for Water Coolers, of which the following is a specification, reference being had to the accompanying drawing, forming part thereof.

The figure is a perspective view of a water cooler, showing my new design.

I claim:

The ornamental design for a water cooler, as shown.

DAVID H. EBINGER.
